UNITED STATES PATENT OFFICE.

HENRY HARRELD, OF SPOKANE, WASHINGTON.

COMBINED RECEPTACLE AND TABLE.

1,306,652.

Specification of Letters Patent. Patented Jan. 25, 1921.

Application filed September 17, 1920. Serial No. 410,836.

To all whom it may concern:

Be it known that I, HENRY HARRELD, a citizen of the United States, and a resident of Spokane, in the county of Spokane and State of Washington, have invented certain new and useful Improvements in Combined Receptacles and Tables, of which the following is a specification.

My invention relates broadly to receptacles and tables, and a purpose of my invention is the provision of a combined receptacle and table which is adapted to be secured to the running board of an automobile, the receptacle serving to house tableware and cooking utensils, and the table, when in extended position, to serve the purpose of a dining table.

I will describe one form of receptacle and table embodying my invention, and will then point out the novel features thereof in claims.

In the accompanying drawings:

Figure 1 is a view showing in perspective one form of receptacle and table embodying my invention in applied position upon the running board of an automobile.

Fig. 2 is a view showing in vertical section the table in extended position upon the receptacle.

Fig. 3 is a view showing in end elevation the receptacle and table, with the latter in extended position.

Fig. 4 is a view similar to Fig. 2 with the table in folded position.

Fig. 5 is a view similar to Fig. 3 with the table in folded position.

Fig. 6 is a longitudinal sectional view taken on the line 6—6 of Fig. 5.

Fig. 7 is a detailed perspective view of one of the hinges used in the table.

Similar reference characters refer to similar parts in each of the several views.

Referring specifically to the drawings, R designates generally the receptacle which, in the present instance, comprises a box 15 and a lid 16 swingingly supported upon the box by means of hinges 17. The lid 16 is provided at all of its edges with depending flanges 18, which, in the closed position of the lid, serve to prevent the passage of dust or other foreign matter into the box. The front edge of the lid is extended to provide a lip 16^a which, as shown in Figs. 2 and 3, extends beyond the forward side of the box when in closed position.

The table is designated generally at T and

comprises a pair of leaves 18 and 19 which are hingedly connected to each other by hinges 20 and to the box by hinges 21. The hinges 20 and 21 are of the construction shown in Fig. 7 wherein it will be seen that the two leaves of each hinge are provided with right angular bent terminal portions. The hinges 21 are connected to the front side of the box 15 and to the leaf 19. These hinges 21 and the hinges 20 are all arranged to allow of the free swinging movement of the leaves from the folded position shown in Fig. 4 to the extended position shown in Fig. 2. In the folded position of the leaves 18 and 19, they are disposed parallel to the front wall of the box 15 and to each other in such manner that with the lid 16 in closed position the lip 16^a will overlie the table leaves. As shown in Fig. 4, the outer side of the leaf 18 lies substantially flush with the forward end of the lip 16^a, the purpose of this arrangement being to effect a locking of the table leaves in folded position by means of a hasp H hingedly supported upon the lid 16 and engaging a staple S secured to the front of the box 15. As shown in Fig. 4, the staple S extends through suitable openings formed in both of the leaves 18 and 19, and as shown in Fig. 1, a padlock is adapted to engage the staple S where it projects from the leaf 18 for locking the hasp thereupon so as to prevent unfolding of the table leaves or opening of the receptacle.

When the table leaves are in extended position, as shown in Figs. 2 and 3, the rear edge of the leaf 19 is disposed below and in contact with the lip 16^a so as to dispose both table leaves substantially in the same plane as that of the box lid 16 and to thereby cause the lid 16 to serve as a continuation of the table T. As shown in Fig. 2, the hasp H passes through the leaf 19 thus permitting the lid 16 to lie perfectly flat on the leaf. The table is supported in extended position by means of a pair of brackets designated at K, which as shown in Figs. 2 and 3, comprise links 22 and 22^a pivotally connected to each other and to the leaf 18 and the side walls of the box 15. The links of each bracket K are adapted to be locked in extended position by means of a sleeve 23 which is slidably fitted upon the links so that it can be moved to spanning or non-spanning position with relation to the pivotal connection between the links. It will be understood that when in spanning position with

relation to this connection, the links are held in extended position, but when the sleeve is moved to non-spanning position, the links can be moved to folded position.

5 In actual use, the receptacle is suitably secured to the running board of an automobile, as illustrated in Fig. 1 so that with the table T in extended position, it will project laterally from the side of the running board 10 and serve as a dining table or for any other desired purpose. The receptacle R is adapted to contain table ware and kitchen utensils ordinarily comprised in camping outfits, the flanges 16^a rendering the receptacle dust 15 proof and thus preventing contamination of its contents.

Although I have herein shown and described only one form of receptacle and table embodying my invention, it is to be understood that various changes and modifications may be made herein without departing from the spirit of the invention and the spirit and scope of the appended claims.

What I claim is:

25 1. In combination, a receptacle comprising a box and a hinged lid having a lip formed on the forward edge thereof and projecting beyond the front of the box when the lid is in closed position, a table comprising 30 leaves hingedly connected to each other and to the front of the box in such manner that when in extended position a portion of one of the leaves engages said lip and when in folded position they are disposed beneath 35 said lip.

2. In combination, a receptacle comprising a box and a hinged lid having a lip formed on the forward edge thereof and projecting beyond the front of the box when the 40 lid is in closed position, a table comprising leaves hingedly connected to each other and to the front of the box in such manner that

when in extended position a portion of one of the leaves engages said lip and when in folded position they are disposed beneath 45 said lip, and means for supporting said leaves in extended position, comprising a pair of foldable brackets, and a sleeve for securing said brackets in extended position.

3. In combination, a receptacle comprising a box and a hinged lid having a lip formed on the forward edge thereof and projecting beyond the front of the box when the lid is in closed position, a table comprising 50 leaves hingedly connected to each other and to the front of the box in such manner that when in extended position a portion of one of the leaves engages said lip and when in folded position they are disposed beneath 55 said lip, means for supporting said leaves in extended position, comprising a pair of foldable brackets, and sleeves for securing said brackets in extended position, and means for locking said lid and leaves in closed position.

4. In combination, a receptacle comprising a box and a hinged lid having a lip formed on the forward edge thereof and projecting beyond the front of the box when the lid is in closed position, a table comprising 60 leaves hingedly connected to each other and to the front of the box in such manner that when in extended position a portion of one of the leaves engages said lip and when in folded position they are disposed beneath 65 said lip, means for supporting said leaves in extended position, comprising a pair of foldable brackets, and sleeves for securing said brackets in extended position, a hasp hingedly supported on said lid, and a staple secured to said lid, said staple being adapted 70 to extend through said leaves and to engage 75 said hasp for the purpose described.

HENRY HARRILD.
